UNITED STATES PATENT OFFICE

148,832

DESIGN FOR AN AUTOMOBILE

Robert A. Walker, Pacific Palisades, Calif., assignor to Harlan F. Gowen, Balboa Island, Calif.

Application April 30, 1946, Serial No. 129,127

Term of patent 3½ years

(Cl. D14—3)

To all whom it may concern:

Be it known that I, Robert A. Walker, a citizen of the United States of America, residing in the city of Pacific Palisades, in the county of Los Angeles, State of California, have invented a new, original, and ornamental Design for an Automobile, of which the following is a specification, reference being had to the accompanying drawings, forming a part thereof.

Figure 1 is a perspective view of an automobile showing my new design;

Figure 2 is a top plan view thereof;

Figure 3 is a side elevational view thereof;

Figure 4 is a front end view thereof; and

Figure 5 is a rear end view thereof.

I claim:

The ornamental design for an automobile, substantially as shown.

ROBERT A. WALKER.
